C. W. KECKLER,
TELEPHONE SYSTEM,
APPLICATION FILED MAY 24, 1917.

Patented Dec. 23, 1919.

Inventor:
Charles W. Keckler.
by *J. E. Roberts* Att'y.

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,325,871.

Specification of Letters Patent. Patented Dec. 23, 1919.

Application filed May 24, 1917. Serial No. 170,601.

To all whom it may concern:

Be it known that I, CHARLES W. KECKLER, a citizen of the United States, residing at Newark, in the county of Essex and State 5 of New Jersey, have invented certain new and useful Improvements in Telephone Systems, of which the following is a full, clear, concise, and exact description.

This invention relates to telephone systems and more particularly to intercommunicating telephone systems.

The principal object of the invention is to provide a simple and efficient arrangement of circuits and apparatus to effect unit- 15 form communication between the different stations of the system, and to this end, electromagnetic means are provided at each station to control the connection of the home line of a calling station with the line of the 20 called station; certain windings of the electromagnetic means at connected stations also serving as impedance or retardation coils through which talking current is supplied directly to each of two or more connected lines.

A further object is to enable another station to be brought into telephonic connection with two or more stations already connected but to audibly indicate to the stations 30 already connected that an attempt is being made to connect in another station. To accomplish this, the relay of the last party called on being energized and signaling another station, connects the line of the 35 called station in the telephonic circuit of the parties already connected while the transmitter of the called station is bridged across the line of that station during signaling and an audible signal arranged in proximity 40 thereto which enables all the stations previously connected to hear the sound produced by the signal at the called station.

This and other features of the invention may be more readily understood by reference 45 to the accompanying drawing, wherein the invention is shown as applied to an intercommunicating telephone system. Three stations, each having lines extending to the other stations, are shown, although obviously 50 a greater number of stations can be furnished if desired. The apparatus and circuits of stations A and B are identical and while the apparatus at station C is identical with the other stations, the circuit differs 55 therefrom by controlling the connection of

the transmitter and receiver across the line of that station through the operation of its hook-switch, whereas at stations A and B the transmitter and receiver are permanently bridged across their respective lines for a 60 reason to be hereinafter described.

In making a call, the calling party will remove his receiver, thus supplying talking battery to his set through two windings of a marginal relay (not operated at this 65 time), these two windings serving as impedance or retardation coils for the calling line. The calling button of the desired station is then depressed and in its lowermost position supplies ringing battery through 70 another winding of the relay which cooperates with the other two windings previously energized to pull up its armature. Ringing battery is also supplied to the bell or other signal at the called station and as 75 the calling station is connected to the line called upon the relay pulling up, the calling party can hear the operation of the signal at the called station provided the transmitter at the called station is bridged across 80 its home line during signaling; as is the case with stations A and B shown.

The party at the called station would remove his receiver from the hook on answering and thereby supply talking battery directly to the called line through two of the windings of the relay at the called station. This relay being marginal does not operate under these conditions but the energized windings serve as retardation coils in sup- 90 plying talking battery to the called station in the same way as the relay at the calling station. On completion of conversation, the parties hang up and the talking windings of the relays are deenergized, whereupon the 95 armature of the relay at the calling station falls back, thereby disconnecting the set from the previously connected line, although the calling button has not been released from its intermediate position. On making an- 100 other call the button first operated is automatically released by depression of another calling button in the usual manner.

To illustrate the operation more in detail, assume that station A wishes to call station 105 B. Receiver at A would first be removed, thereby supplying current from a common talking battery 5 over a circuit extending from battery 5, conductors 6 and 7, right-hand winding of marginal relay 8 individ- 110

ual to station A, conductor 9, switch contact 10 in upper position, conductor 11, transmitter and receiver of station A, conductor 12, switchhook 4 and upper contact, conductor 13, middle winding of relay 8 (wound in series aiding relation to the right-hand winding thereof) and conductors 14 and 6' to the other side of battery 5. The relay 8 is so margined that it will not pull up except 10 on energization of all three windings which increases the effective ampere turns of the relay windings to effect its operation. After being pulled up, however, this relay will be maintained in operative position so long as 15 the middle and right-hand windings remain energized.

These last mentioned windings perform the function of retardation coils in supplying talking battery to the set with which 20 they are connected. This arrangement is important as it supplies each station with talking battery directly through certain windings of the relay individual thereto, as soon as the receiver is removed from its hook 25 so that connected stations are each directly supplied with talking current, thus improving communication between the stations and greatly increasing the transmitting efficiency.

After removing his receiver the party at 30 A will depress a calling key K^2 individual to station B. This key in common with the other calling keys K' , K^3 and K^4 , is designed to be depressed as far as it will go in calling so as to contact with the lowermost spring 35 of the key and to engage the center spring thereof with a bus bar 15. The keys remain in the lowermost position only so long as they are manually held there by the person calling, and return to an intermediate position 40 in which they are held by the usual locking plate 16 as soon as pressure on the calling button is relieved. In intermediate position only the first and second and third and fourth springs, respectively, of the key 45 are engaged. The operation of any key in calling releases any other key which may have remained in locked position, although as hereinafter explained, it is not necessary that keys which may be in locked position 50 at a called station be released to obtain connection with the calling line or to prevent interference by other parties; although generally necessary heretofore in systems of this kind.

55 The bus bar 15 is connected to one side of a ringing battery 17 by a conductor 18, extending to one wire 19 of the common ringing battery wires 19 and 19' and on full depression of the key K^2 , a circuit is 60 completed to operate a signal 20 at station B; this circuit extending from battery 17 conductors 19 and 18, bar 15, third spring of key K^2 , conductor 21, line wire 2, conductor 22, hook switch 23 and lower contact, 65 conductor 24, armature and winding of sig-

nal 20, conductor 25 and lead wire 19' to the other side of ringing battery. The signal 20 interrupts its own circuit and continues to operate only so long as the key K^2 is held in its fully depressed position.

A circuit is also closed at this time to energize the left-hand winding of the relay 8 to coöperate with the other two windings previously energized to pull up the armature thereof. This circuit extends from signal 70 battery 17, conductors 19 and 18, bus bar 15, third spring of key K^2 and fourth and fifth springs thereof, conductors 27 and 28, left-hand winding of relay 8, conductors 29 and 19' to the other side of battery. The 75 operation of the relay 8 serves to connect the set at station A with the line wires 2, 2' of station B and inasmuch as the telephone set of station B is bridged across these line wires during signaling, by using an audible 80 signal 20 and locating it in proximity with the transmitter of the set, the calling party at A will hear the sound of the signal 20 reproduced by the transmitter at station B and will know that the line is idle and that 85 the signal is being received, whereas if the line is busy, the signal will not be operated and the calling party hearing nothing will know the called line is busy. Assuming 90 station B to be idle, the circuit to render the 95 operation of the signal 20 audible to station A is in parallel with the talking circuit of station A previously traced and commences at conductor 11, thence by conductor 30 to outer arm and front contact of relay 8 (now 100 energized), conductors 31 and 32, second and first springs of key K^2 , conductor 33, line wire 2', conductor 34, transmitter and receiver of the set at station B to conductors 22 and 2, conductor 21, third and fourth 105 springs of key K^2 , conductors 36 and 37, inner armature and front contact of relay 8, which armature is connected to conductor 12 and completes the parallel circuit.

This feature is of considerable advantage, 110 as hearing the actual sound given off by the signal at the called station gives a distinctive indication not liable to be confused with other signals, which has proved an objectionable feature where tone signals have 115 been used.

If this feature of the invention is not desired for any reason, it is only necessary to arrange the transmitter so that it is not in circuit while its signal is being operated. 120 This may be done by arranging the switchhook to close the circuit thereto only when the hook is up and the signal disconnected, and the telephone set at station C illustrates such an arrangement. The same result may 125 also be obtained by arranging the audible signal at station C in such a way that the sound therefrom will not actuate the transmitter or by using a visual rather than an audible signal.

The party at station B on hearing his signal would respond by removing his receiver from the hook, whereupon as previously explained for station A, talking battery will be supplied directly to the telephone set of station B through the middle and right-hand windings of relay 38. This circuit extends from battery 5, conductors 6 and 39, right-hand winding of relay 38, conductor 40, upper position of contact 41, conductor 34, transmitter and receiver of station B, conductor 22, switchhook 23 and upper contact (now closed), conductor 42, middle winding of relay 38, conductors 43 and 6', to the other side of battery. Relay 38 being marginal will not pull up when station B is the called station as previously explained but the middle and right-hand windings nevertheless serve as retardation coils in supplying talking battery thereto, thus providing both of the connected stations directly with talking battery through their respective relays 8 and 38. This provides better transmission than where but one of the stations is supplied directly with talking battery and the other stations connected therewith are supplied indirectly through the first station as has been the general practice in intercommunicating systems heretofore.

It will be observed that the connection of station B is independent of the position of any of the calling keys thereat, and the line to any station whose calling key might be in locked position at station B would not be connected, as the only connecting circuit is through the conductors 44 and 45 and the front contacts and armatures of the relay 38 which is not pulled up while station B is serving as a called station.

For the purpose of illustrating how two connected stations can bring another station in telephonic connection with the connected lines and at the same time give an audible indication to those already connected that such an attempt is being made, assume that station A has called station C and that the two stations are in telephonic communication. Assume that the party at station C desires to enable the party at station B to hear or join in the conversation either with or without the consent of the party at station A. Station C being the called line, the relay 48 thereat would not be pulled up although the middle and right-hand windings would be energized. Therefore, the full depression of the key K² individual to station B, at station C would energize the left-hand winding of the relay 48, which would thereupon pull up, as previously explained for the relay 8, at station A (C now acting as a calling station). The relay 48 pulling up and co-operating with the K² would connect the telephone set at station B C with the lines wires 2 and 2' of station B

and station A being already connected with station C would also be connected with the line wires of station B through the apparatus of station C. At the same time the circuit energizing the left-hand winding of the relay 48 is closed. The signaling circuit to station B is also closed to operate the audible signal 20, this circuit being similar to that described when station A signaled station B.

Inasmuch as the transmitter of the set at B is bridged across its line during signaling and the signal 20 located in proximity thereto, the operation of the signal would be audible to station C and also to any other stations which are in telephonic communication with station C when the latter calls station B. In this way, such other stations would be apprised of the fact that an attempt was being made to bring in a party at another station and enable them to take appropriate action in the event they did not wish the inclusion of the additional party for any reason.

The party at station B in responding would remove his receiver from the hook in the usual manner and supply talking current directly to his set through the middle and right-hand windings of the relay 38 as previously explained. Stations A and C were already in telephonic communication at the time station C called station B, and as a similar connection is provided between stations C and B, stations A and B are brought into telephonic communication through the apparatus at station C so that all three parties can converse freely together. Disconnection would be effected by the hanging up of the receivers in the usual manner and result in the deenergization of the relays 8 and 48 in the manner previously described, to restore the apparatus to normal position.

What is claimed is:

1. In a telephone system, a plurality of line circuits, a telephone set associated with each line circuit, a relay individual to each of said telephone sets and having a winding, switching means individual to each of said telephone sets operable to effect the operation of one of said relays to connect two of said line circuits together, and a common source of talking current for said telephone system; said winding of each of the relays of connected line circuits being interposed between said source of current and its respective telephone set and serving as impedance means for talking current supplied to the telephone set individual thereto during such connection.

2. In a telephone system, a plurality of line circuits, a telephone set including a receiver and hook therefor associated with each line circuit, a relay individual to each telephone set and having a winding, switching

- means individual to each of said telephone sets operable to effect the operation of one of said relays to connect two of said line circuits together, a common source of talking current for said telephone system, means individual to each telephone set to supply current through its respective relay to such set directly on removal of the receiver of the set from its hook; said relays being interposed between said source of current and its respective telephone set and serving as an impedance means for talking current supplied to the telephone set individual thereto.
3. In a telephone system, a plurality of line circuits, a telephone set including a receiver and a hook associated with each of said line circuits, a relay individual to each of said telephone sets to connect two of said line circuits together, said relay having a plurality of windings, a source of current for said telephone system, means individual to each set to supply current to its respective set through a winding of the relay individual thereto directly on the removal of its receiver from its hook, switching means for each of said line circuits adapted to supply current through another of said relay windings to actuate said relay; the first mentioned of said windings serving as impedance means for talking current supplied to its respective set.
4. In a telephone system, a plurality of line circuits, a telephone set including a receiver and hook associated with each of said line circuits, a marginal relay having a plurality of windings associated with each of said telephone sets to connect two of said line circuits together, a source of current for said system, means individual to each set to control the supply of current to said set through certain of said relay windings on removal of the receiver from its hook, said certain of said relay windings serving as an impedance means, and switching means associated with each of said line circuits adapted to supply current to certain other of said windings to coöperate with the remaining windings to operate said relay, energization of said impedance windings serving to maintain said relay in operative position.
5. In a telephone system, a plurality of line circuits, a telephone set including a receiver associated with each of said line circuits, a relay having a plurality of windings and individual to each of said telephone sets to connect two of said lines together, a receiver switch for each of said sets to supply talking battery to its set directly on removal of the receiver through one or more of said relay windings, said one or more windings serving as impedance

means therefor, means at each of said sets to supply signaling current through one winding of the relay of the calling set to operate the signal at a called set, said relay requiring energization of the winding traversed by signaling current in order to operate and being maintained in operative position by energization of said one or more windings traversed by talking current.

6. In a telephone system, a plurality of line circuits, a plurality of telephone sets, a relay having a winding and individual to each set to connect its associated set with one of the line circuits, means for supplying current to one of the telephone sets through a winding of its respective relay without operating such relay, and means to increase the effective ampere turns of such relay to operate such relay to connect its respective set with one of the line circuits.

7. In a telephone system, a plurality of line circuits, a telephone set including a transmitter associated with each line circuit, means to telephonically connect two of said line circuits together, means associated with one of said connected line circuits to telephonically connect another line circuit to those already connected, an audible signal associated with said other line circuit, means operated incident to connecting said other line circuit to line circuits previously connected to operate said signal, and connections operatively associating the transmitter of the set of said other line circuit with such circuit during signaling of such set to render the sound produced by said signal audible to the sets of said previously connected line circuits through the medium of such transmitter.

8. In a telephone system, a plurality of line circuits, a telephone set comprising a receiver and transmitter associated with each line circuit, means associated with each of said line circuits to connect it to another line circuit, said means being operable only when the line circuit is the calling line, an audible signal individual to each of said telephone sets and arranged in proximity thereto, and means operated incident to the connection of another line circuit to operate said signal, the transmitter of the set signaled being connected across its line circuit during signaling, whereby the sound produced by said signal is communicated to the set of the line calling and also to any other sets which are in telephonic connection with a line circuit calling another line circuit.

In witness whereof, I hereunto subscribe my name this 22nd day of May A. D., 1917.

CHARLES W. KECKLER.
